E. C. PETERS

ROTARY PUMP

Filed Feb. 3 1927

INVENTOR.

Edward C. Peters.

BY

ATTORNEY

UNITED STATES PATENT OFFICE.

EDWARD C. PETERS, OF DETROIT, MICHIGAN.

ROTARY PUMP.

Application filed February 3, 1927. Serial No. 185,530.

My invention relates to a new and useful improvement in a rotary pump, and has for its object the provision of a rotary pump which may be used as a pump generally, but is especially adapted for use on mechanical refrigerators for compressing the refrigerating fluid.

It is an object of the invention to provide a pump of this class which will be noiseless, continuous in operation, pumping a maximum volume, adapted for great speed, and one which can be produced and operated at a minimum cost.

Another object of the invention is the provision of a pump of this class which may be utilized for transmitting power where the use of belts is undesirable.

Another object of the invention is the provision of a pump of this class which will be compact so as to be adapted for mounting in small spaces, and which will be quite positive in its operation.

Another object of the invention is the provision of a pump of this class which may be easily and quickly assembled.

Another object of the invention is the provision in a pump of this class of a cam operated blade so arranged as to be in contact with the inner surface of the stator at all times without necessitating the use of springs.

Other objects will appear hereinafter.

The invention consists in the combination and arrangement of parts hereinafter described and claimed.

The invention will be best understood by a reference to the accompanying drawings which form a part of this specification, and in which,

Fig. 1 is a side elevational view of the invention.

Fig. 2 is a longitudinal central vertical sectional view of the invention taken on line 2-2 of Fig. 3.

Fig. 3 is a sectional view taken on line 3-3 of Fig. 2.

Fig. 4 is a perspective view of one of the blades used in the invention.

As shown in the drawings, the invention embodies a stator comprising a cylindrical shell 9 having an eccentric bore 10 formed therein. Adapted for engaging rotatably in the shell 9 is a cylindrical rotor 11, the outside diameter of this rotor 11 being such that it engages the inner surface of the shell 9 at diametrically opposite sides, the

inner surface of the shell 9 being formed elliptical, so that at diametrically opposite sides, the rotor 11 engages the inner surface, and at diametrically opposite sides at right angles thereto, there is considerable space between the inner surface of the shell 9 and the periphery of the rotor 11. Formed in one end of the rotor 11 is a socket 12 and a shaft 13 is fixedly mounted on the rotor 11 and projects therefrom, this shaft extending through a bushing 14 mounted in the cap 15 which is secured by the screws 16 to one end of the shell 9. There is shown mounted on the shaft 13 a pulley 17 whereby power may be transmitted from the pump. The shaft 13 is provided with a reduced portion 18 engaging in a bushing 19 positioned in a socket 20 formed in the shaft 21, the reduced end 22 of which engages in the bore 23 formed in the cap 24 which is secured by the screws 25 on the opposite end of the shell 9, the shell 9, together with the caps 24 and 15 forming a housing which constitutes the stator. A set screw 26 engages the reducing portion 22 so as to retain the shaft 21 in fixed relation. Mounted on the free end of the shaft 21 is a cam 27.

Formed in the periphery of the rotor 11 are a number of grooves 28, each communicating through an opening 29 with the socket 12. Positioned in each of the grooves 28 is a blade 30 having its outer edge curved, this outer edge being struck on the same circle that is determined by the periphery of the rotor 11. Extending inwardly from each of the blades 30 through the opening 29 is an arm 31 carrying on its inner end a roller 32 to engage the periphery of the cam 27.

Formed in the shell 9 is an inlet port 33 and an outlet port 34, these inlet and outlet ports co-operating. There is also formed an inlet port 35 which is preferably positioned diametrically opposite to the inlet port 33, and there is formed an outlet port 36 co-operating with the inlet port 35 and positioned diametrically opposite to the outlet port 34. By loosening the set screw 26, the shaft 21 may be adjusted so that the cam will be properly positioned to engage the rollers 32 and retain the blades 30 in engagement with the inner surface of the shell 9 at all times, so that as the blade approaches the inlet port 33, it will force ahead of it such water or other fluid as may be present in the direction of the outlet port

34. The use of the plurality of inlet ports and outlet ports permits the use of a small device, while at the same time, productive of great capacity, and the location of the 5 inlet and outlet ports in proximity to each other adds to the efficiency of the device as the rotor is thereby forced to carry or force the fluid a minimum distance.

It is believed evident that the device is 10 compact and that it may be easily and quickly assembled, removal of one of the caps being sufficient to permit entry into the stator for making the necessary adjustments or removing the various parts required to be 15 removed and replaced.

If desired, this pump may be used for 20 transmitting power as one of the pumps may be positioned in a suitable location for forcing liquid through a piping to another 25 pump located in close proximity to the machine to be driven, this machine being, if desired, coupled directly to the shaft 13. In this manner, it becomes possible to drive machinery in various parts where the use 25 of chains is undesirable or quite impossible.

While I have illustrated and described the preferred form of my invention, I do not wish to limit myself to the precise form of structure shown, but desire to avail myself of such variations and modifications as may come within the scope of the appended 25 claim.

Having thus described my invention what

I claim as new and desire to secure by Letters Patent is:

A rotary pump of the class described having 35 a stator, comprising: a cylindrical shell having an eccentric inner surface; a cap mounted on each end of said shell; a cylindrical rotor rotatably mounted in said shell; 40 a shaft on said rotor projecting through one of said caps and one end of, and rotatable with, said rotor, said rotor having a socket formed in its opposite end; a reduced portion 45 on said shaft projecting into said socket; a shaft fixedly mounted on the other cap and projecting into said socket, said shaft having a socket formed on its inner end for the reception of said reduced portion; a cam mounted on the inner end of said 50 shaft, extending radially outwardly from said reduced portion, said stator having a plurality of axially extending peripheral grooves; a blade radially movable in each of said grooves; an arm on each of said blades projecting inwardly into the socket formed in said rotor; a roller on the inner end of each of said arms engaging the periphery of said cam, said cam retaining said 55 blades in engagement with the inner surface of said shell, at all positions of rotation of said rotor, said stator having co-operating inlet and outlet ports formed therein.

In testimony whereof I have signed the foregoing specification.

EDWARD C. PETERS.
